UNITED STATES PATENT OFFICE.

ARTHUR M. WENTWORTH, OF PITTSFIELD, MASSACHUSETTS, ASSIGNOR TO GENERAL ELECTRIC COMPANY, A CORPORATION OF NEW YORK.

INSULATED WIRE AND TERMINAL THEREFOR.

1,157,916.

Specification of Letters Patent.

Patented Oct. 26, 1915.

Application filed August 24, 1914. Serial No. 858,168.

To all whom it may concern:

Be it known that I, ARTHUR M. WENTWORTH, a citizen of the United States, residing at Pittsfield, in the county of Berkshire, State of Massachusetts, have invented certain new and useful Improvements in Insulated Wire and Terminal Therefor, of which the following is a specification.

My invention has reference to the manufacture of sheathed wire comprising a resistance conductor embedded in insulating material which is inclosed in a metallic sheath. A successful method for manufacturing wire of this character is fully disclosed in an application which was filed by Chester N. Moore, Serial No. 837,873, on May 11th, 1914, to which reference may be had for fuller details as to manufacture. Briefly, however, it may be stated that wire of this character is now made by first forming a blank or ingot composed of a metal core which, when the finished product is to be used for heating purposes, should be of high resistance material; this core is arranged at the center of a metal tube which is ordinarily composed of steel or copper, and the space between the core and the tube is packed with a refractory powdered heat insulating material which is capable of being compressed to a high degree. The whole is then swaged down in a swaging machine until the insulating material is thoroughly compacted and until it reaches a condition resembling, in its physical properties, the character of a metal, and the entire unit approximates a condition of homogeneity throughout. When the sheathed wire has reached this condition, further reduction of the wire is made, either by swaging or by other processes such as rolling or drawing, until the resistance member is of the required cross-section and until the layer of insulating material between the resistance conductor and the sheath becomes very thin. Now, the resistance conductor of sheathed wire made in the manner indicated above is of substantially uniform cross-section, and one of the serious obstacles to the use of sheathed wire of this character has been the difficulty of satisfactorily securing terminals from the supply circuit to the resistance wire. When plain sheathed wire is used the resistance conductor must necessarily project beyond the end of the insulating material and sheath, and, as the re-

sistance wire is very small, the manipulation necessary in securing the terminal to the wire is liable to result in the resistance wire being broken. Furthermore, an operation such as-brazing is usually required to 60 secure the terminal to the resistance wire, and this causes the resistance wire to become highly heated, and this is liable to result in its crystallization, which may cause it to deteriorate in use. In addition to this, the 65 heat is not conducted away from that part of the resistance wire which is bathed in air, and which is adjacent the terminal, as rapidly as it is from the wire which is inclosed in the sheath, and the part of the wire 70 which is adjacent the terminal accordingly runs at a higher temperature than the remainder of the resistance. This high temperature, coupled with the fact that the resistance member is exposed to the air, is 75 liable to result in the rapid oxidation and deterioration of the resistance wire.

In its more specific aspect, my invention has for its object the provision of sheathed wire of the character indicated above formed 80 with an enlarged terminal, preferably integral with the resistance wire.

In its broader aspect, however, my invention has for its object the provision of sheathed wire of the character indicated 85 provided with one or more enlarged sections of the resistance wire at any desired point.

For a fuller understanding of my invention, reference may be had to the accompanying drawings, in which—

Figure 1 is a longitudinal section of a blank or ingot from which the sheathed wire may be made; Fig. 2 is similar to Fig. 1, but shows the ingot reduced in cross-section; Fig. 3 is similar to Fig. 2, but with the plug 95 at the end removed and the end of the sheath stripped to expose the end of the core wire; Fig. 4 is similar to Fig. 3, but with the end of the sheath reduced to a taper; Fig. 5 shows the process carried a step farther, in 100 which the external diameter of the sheath is uniform and the taper at the end of the sheath transferred to the inside of the sheath; Fig. 6 is similar to Fig. 5, showing the sheath closed against the metallic core; 105 Fig. 7 shows the wire after a further reduction takes place; Fig. 8 is similar to Fig. 7, but showing the sheath and insulating material stripped so as to expose enough of the core wire to form a terminal; Figs. 9 and 10 110

show a modification of my invention in which my process is applied to the formation of an enlarged section within the sheath, where it makes the same suitable for a support, Fig. 9 showing a section removed from the outer portion of the sheath, and Fig. 10 showing the same reduced until the metallic sheath is of a substantially uniform external diameter; Figs. 11 and 12 show still another modification, in which my invention is applied to the formation of an enlarged section of the core wire which makes the same particularly suitable for a branched electric connection.

Referring now to the drawings, and first to Figs. 1 to 8, which illustrate my invention applied to the manufacture of sheathed wire provided with an enlarged terminal, 1 in Fig. 1 is a metallic core, usually made of a high resistance material which is sufficiently ductile to permit of its being reduced by known processes to a diameter which makes it suitable as a resistance conductor. This core is arranged at the center of the metallic tube 2, the space between the core and the tube being packed with refractory powdered insulating material 3, such as magnesia or lime. The end of the tube is closed by means of plugs 4. The ingot is now reduced, preferably in a swaging machine of any suitable design, until the insulating material is thoroughly compacted and reaches a condition resembling, in its physical characteristics, a metal, at which time the sheathed wire may be bent and treated in general as an ordinary wire without disturbing the relation of the component parts. This preliminary reduction should usually also be carried to a point where the core wire is of the proper size to form a terminal. The end of the sheath and the plugs are then removed, as indicated in Fig. 3, one end only being shown, in order to bare the core wire. The end of the sheathed wire is now turned down to a taper, as at 5, so that the external diameter of the end of the sheath is less than the middle, and so that the wall of the sheath is thinner at the end than in the middle. The sheathed wire is then further reduced by swaging or by other processes if desirable, such as rolling or drawing, as indicated in Fig. 5. During this stage of the process the end of the core wire is relieved or partially relieved of the pressure exerted by the dies or rolls through the insulating material in proportion to the thickness of the material that has been removed from the outer sheath, with the consequence that the diameter of the end of the core wire remains about the same as it was at the previous stage, that is to say, about the same as that shown in Fig. 4, while the body of the resistance core is further reduced. This process results in the formation of an enlarged terminal 6 integral with the resistance wire,

the portion of the core where the change in diameter occurs being surrounded by the insulating material. During this reduction, the taper at the end of the sheath is transferred from the external part of the sheath to the internal part, as indicated at 7, and the end of the core wire being relieved of the pressure from the dies or rolls in proportion to the thickness of the material that has been removed from the sheath, the end of the core wire takes on a taper corresponding to the taper of the sheath.

While the succeeding step of the process is not absolutely essential to the formation of satisfactory sheathed wire with an enlarged terminal, I prefer to place the end of the sheathed wire in a die and subject the same to pressure, thereby closing the sheath against the core wire, as at 8 (see Fig. 6). The previous operations involved will result in a certain amount of insulating material being removed from the end of the sheath, as at 9 (see Fig. 5), and with a little experience the operator will be able to ascertain about the amount that should be removed in order to leave the insulating material at the end of the sheathed wire, after the sheath has been closed against the core, of about the same density as that in the remainder of the sheath. The reduction is now continued until the resistance wire has attained the proper size. With the end of the sheath closed against the resistance wire, this may be accomplished without danger of further insulating material being removed from the sheath. Finally, the end of the sheath and the insulating material are removed, leaving a sheathed wire of the form shown in Fig. 8 with an enlarged terminal 6, the sheath having a substantially uniform external diameter, and the portion of the wire where the change of cross-section occurs being surrounded by insulating material.

The terminal formed in accordance with the foregoing process may be used directly as a terminal, and as the cross-section of the same is much greater than that of the resistance wire, the terminal runs much cooler and there is no danger of the same deteriorating in use; or, if desired, terminals may be brazed, or otherwise secured to this terminal, without danger of injuring the same.

It is sometimes desirable to run a section or sections of the sheathed wire cooler than the remainder, as, for example, where the same is to be supported. This condition may arise where the sheathed wire is coiled back and forth to form a heating unit, and where it becomes desirable to support the sheathed wire at the ends of the coils. In Figs. 9 and 10 I have illustrated sheathed wire made in accordance with my invention suitable for this purpose. The section of the outer sheath from which the wire is to be

supported is reduced, as indicated, at 4^a. The sheathed wire is then reduced, and this reduction will result in the formation of an enlarged section 10, as indicated in Fig. 10, and for the same reasons as explained in connection with the formation of the enlarged terminal.

Figs. 11 and 12 show my invention applied to the formation of an enlarged section of the core wire, which particularly adapts the same for connection to a branch wire. For this purpose, a small section of the outer sheath 4^b is removed, and when the sheathed wire is swaged or otherwise reduced a short enlarged section 9^a will be formed on the wire. An opening may now be made in the sheath and insulating material, and an electrical connection be made to the resistance wire at this point. I am aware of a patent granted to Willis R. Whitney, No. 1,093,512, which was issued April 14, 1914, and I do not herein claim broadly a sheathed wire provided with an enlarged terminal, or the process of making the same.

Since the only portion of the resistance conductor in the sheathed wire, made in accordance with my process, which is exposed to the atmosphere, is the enlarged terminal, the wire may be used without danger of the terminal's being burned out or broken. The section of the wire where the change of cross-section occurs is surrounded by the refractory insulating material, so that all of that portion of the resistance conductor which is run at a high temperature is entirely surrounded by the insulating material, and there is no danger of the same being oxidized, as the air is excluded.

It will be understood that the terminal formed in accordance with my invention may, if desired, be surrounded by a jacket filled with refractory insulating material, but ordinarily it will be found that a separate inclosing jacket is unnecessary.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:

1. The method of forming a sheathed wire from an ingot in which a conductor is embedded in insulating material surrounded by a metallic sheath which consists in reducing the entire sheath and conductor by consecutive passes through a reducing machine and partially relieving the pressure on a portion of the conductor during a stage of the re-

ducing operation and thereby leave the conductor larger in section at said portion.

2. The method of forming a sheathed wire from an ingot in which a conductor is embedded in insulating material surrounded by a metallic sheath which consists in reducing the entire sheath and conductor by consecutive passes through a reducing machine, and treating a portion of the sheath at an intermediate stage of the reducing operation so that during the last stage of the reducing operation the conductor in that portion is reduced in section less than the main body of the conductor.

3. The method of forming sheathed wire with a conductor of variable cross-section from an ingot in which a conductor of substantially uniform cross-section is embedded in an insulating material and surrounded by a metallic sheath which consists in forming the metallic sheath with a variable external diameter and then reducing the sheathed wire.

4. The method of forming sheathed wire with a conductor having an enlarged terminal from an ingot in which a conductor is embedded in an insulating material surrounded by a metallic sheath which consists in removing an outer layer from the end of the sheath and then reducing the sheathed wire.

5. The method of making sheathed wire having an enlarged terminal from an ingot composed of a metallic core embedded in insulating material surrounded by a metallic sheath, which consists in removing an outer layer from the end of the sheath to form a taper and then reducing the sheathed wire.

6. The method of forming sheathed wire with an enlarged terminal, which consists in swaging down an ingot formed of a metallic core embedded in insulating material inclosed in a metallic sheath until the core is of a size suitable for a terminal, reducing the external diameter of a portion of the sheath, and then reducing the sheathed wire.

7. The method of making sheathed wire which consists in forming a metallic core surrounded by refractory heat insulating material inclosed in a metal sheath, reducing the outside diameter of a portion of the sheath and then reducing the sheathed wire.

8. The method of making sheathed wire provided with an enlarged terminal which consists in forming a metallic core surrounded by refractory heat insulating material inclosed in a metal sheath, reducing the outside diameter of the end of the sheath and then reducing the sheathed wire.

9. The method of making sheathed wire provided with an enlarged terminal which consists in forming a metallic core surrounded by refractory heat insulating material inclosed in a metal sheath, reducing

the outside diameter of the end of the sheath to a taper and then reducing the sheathed wire.

10. The step in the method of making sheathed wire from an ingot comprising a metallic core embedded in powdered insulating material surrounded by a metallic sheath by swaging, which consists at an intermediate stage of the process in closing the sheath against the core.

11. As an article of manufacture, sheathed wire comprising a resistance conductor formed with an enlarged section embedded in refractory insulating material and surrounded by a sheath having a substantially uniform external diameter which compacts the material against the conductor.

12. As an article of manufacture, sheathed wire comprising a resistance wire embedded in powdered refractory insulating material and surrounded by a metallic sheath which compacts the material against the conductor,

the resistance conductor being provided with an enlarged terminal, and the sheath having a substantially uniform external diameter.

13. As an article of manufacture, sheathed wire comprising a resistance conductor embedded in refractory insulating material inclosed in a metallic sheath which compacts the material against the conductor, the resistance conductor being provided with an integral enlarged terminal, the portion of the conductor where the change in cross-section occurs being surrounded by the insulating material, and the sheath having a substantially uniform external diameter.

In witness whereof, I have hereunto set my hand this 20th day of August, 1914.

ARTHUR M. WENTWORTH.
